(57) **CLAIM**

The ornamental design for a flat panel display stand, as shown and described.

DESCRIPTION

FIG. 1 is a perspective view of a flat panel display stand, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a right side elevational view thereof, with the broken line showing of a flat panel display forming no part of the claimed design.
